UNITED STATES PATENT OFFICE.

ANDREW BOLLAK, OF HOMER CITY, PENNSYLVANIA.

FIGURE TOY.

Application filed March 1, 1928. Serial No. 258,365.

This invention relates to an improved figure toy, wherein the figures are constructed to represent persons operating individual wood saws, whereby to provide a toy which 5 will provoke amusement for small children.

More specifically, the invention comprises a slotted platform on which two figure are mounted. The figures include movable portions having imitation arms pivotally reciprocable imitation saws operating through the slots, and mechanical operating means provided for the saws and the figures.

The particular details and their relative arrangement and association will become 15 more readily apparent from the following description and drawings.

In the drawings:

Figure 1 is a sectional and elevation view 20 of the complete toy showing the general arrangement and association of parts.

Fig. 2 is an end view of the same, and

Fig. 3 is a horizontal section through the box.

In carrying out the invention, I provide a 25 hollow box 4 having a top 5 provided with an elongated slot or opening 6. Mounted on the top and at the opposite ends of the openings, we find individual figures 7 and 8. Each figure comprises stationary legs 9 and a 30 swingably mounted body 10.

Each body includes imitation arms 11 whose hands are pivotally connected with imitation saws 12. The saws are formed by serrating the edges of a pair of pitman rods 35 13, these being eccentrically connected with a pair of intermeshing gears 15, and 16.

An operating shaft 17 is connected with the gear 15, and this carries crank handles 18 located on the exterior of the box for convenient operation.

It is obvious that by grasping and turning the hand crank 18, the gears 15 and 16 will serve to alternately reciprocate the pitman rods 13 through the slot 6 in the top of the 45 box. Since these pitman rods are connected with the movable body portions of the figures, it is obvious that the figures will move up and

down successively and this is indicated in Fig. 1, thereby representing two workmen sawing wood.

The construction, operation and advantages of the invention will be clear after reading the description in connection with the drawings. Therefore, a more lengthy description is regarded unnecessary.

Minor changes in shape, size and rearrangement of parts coming within the field of invention claimed, may be resorted to if desired.

Having thus described my invention, what I claim as new is:

1. In a figure toy of the class described, a hollow box having the top provided with an elongated slot, figures mounted on the exterior of the top at opposite ends of the slot, 65 said figures each including a stationary leg portion and a swingably mounted body portion, said body portion including imitation arms, vertically disposed imitation saws connected with said arms and extending down 70 into the box through said slot, and operating means within the box for alternately reciprocating said imitation saws whereby to successively operate the movable body portions of said figures, said operating means constituting intermeshing gears with which said saws have eccentric pivotal connection.

2. In a figure toy of the class described, a body having a top provided with an elongated slot, figures mounted on said top and including stationary leg portions and movable body portions, intermeshing gears located inside of said box, pitman rods pivotally and eccentrically connected with said gears to produce alternate operation of said pitman rods, one edge of the pitman rods being serrated to provide an imitation saw and the pitman rods being connected at their upper ends with the movable body portions of said figures, and a hand crank for operating said gears.

In testimony whereof I affix my signature.

ANDREW BOLLAK.
